UNITED STATES PATENT OFFICE

109,971

DESIGN FOR A COFFEE GRINDER

George P. Anderson and Douglas G. Anderson,
Detroit, Mich., assignors to The Standard Com-
puting Scale Company, Detroit, Mich., a cor-
poration of Michigan

Application December 23, 1937, Serial No. 73,835

Term of patent 14 years

To all whom it may concern:

Be it known that we, George P. Anderson and Douglas G. Anderson, citizens of the United States, residing at Detroit, in the county of Wayne and State of Michigan, have invented a new, original, and ornamental Design for a Coffee Grinder, of which the following is a specification, reference being had to the accompanying drawing, forming part thereof.

Figure 1 is a perspective view of a coffee grinder, showing our new design; and

Figure 2 is a top plan view thereof.

We claim:

The ornamental design for a coffee grinder, as shown.

GEORGE P. ANDERSON.
DOUGLAS G. ANDERSON.
